UNITED STATES PATENT OFFICE.

ABRAHAM VELLEMAN, OF NEW YORK, N. Y.

WIRE-FRAME MACHINE.

No. 830,265.

Specification of Letters Patent.

Patented Sept. 4, 1906.

Application filed March 28, 1905. Serial No. 252,546.

To all whom it may concern:

Be it known that I, ABRAHAM VELLEMAN, a citizen of the United States, and a resident of the city of New York, borough of Manhattan, in the county and State of New York, have invented a new and Improved Wire-Frame Machine, of which the following is a full, clear, and exact description.

The purpose of my invention is to improve upon the construction of the wire-frame machine for which application for patent was made December 13, 1904, Serial No. 236,887, the improvement being principally to so construct and mount the frame-supporting arms that their inner ends may be set relatively to a given center and their outer ends adapted as required to any point in a circular circuit and whereby the arms may be adjusted independently in a lateral or rotary direction as may be required by the conditions of the work.

A further purpose of the invention is to provide a very simple machine of the type described and one wherein the parts may be readily and quickly adjusted to adapt the machine for the formation of any style of wire-frame hat, regular or irregular in general contour, and also to provide a centering device having means for adjustment, enabling the device being placed in position to accurately center the crown of any wire-frame hat, and, furthermore, to so construct the machine that it can be adapted to any shape of crown and so that after a shape has been completed it can be readily and quickly freed from the machine without danger of injuring the shape.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a plan view of the machine. Fig. 2 is a sectional plan view taken substantially on the line 2 2 of Fig. 3. Fig. 3 is a vertical section taken substantially on the line 3 3 of Fig. 1. Fig. 4 is a horizontal section taken practically on the line 4 4 of Fig. 3. Fig. 5 is a horizontal section through the base, taken substantially on the line 5 5 of Fig. 6. Fig. 6 is a vertical section through the base, taken substantially on the line 6 6 of Fig. 5. Fig. 7 is a perspective view of the

head-section of the centering element. Fig. 8 is a perspective view of one of the shoes adapted to have rocking support in the base and in which the standards of the supporting-arms are adjustably secured. Fig. 9 is a side elevation of one of the upper members of one of the supporting-arms, parts being broken away and some of the clamps for the framing members carried thereby being in section. Fig. 10 is a transverse section through the upper member of the supporting-arm shown in Fig. 9, a section through a clamp carried thereby, and a side elevation of a portion of the framing member held by the clamp. Fig. 11 is a perspective view of a portion of a modified form of an upper or carrying member for a supporting-arm and a clamp adapted thereto, and Fig. 12 is a transverse section through the carrying member shown in Fig. 11 and its clamp.

The base A is preferably made in sections, as is illustrated in Figs. 3 and 6, comprising primarily a hollow bottom section a and a table-section a'. The hollow bottom section 80 consists of a body 10, containing a chamber 10^a open at its lower portion, and a tubular standard 11, which is attached to or constitutes an integral portion of the top of the body, the standard being in communication 85 with the chamber 10^a and a flange 11^a, adapted to rest upon any desired support. The table-section a' consists of a disk body 12 and a tubular hub 13, which extends downward from the body at its center. The hub 90 13 is enlarged where it connects with the disk body 12 of the table to provide a chamber 14 open at the top, which chamber is of greater diameter than the bore of the hub below it, and at the upper marginal portion of 95 this chamber the upper face of the body 12 is beveled from a point about centrally between its inner and outer edge portions downward to said chamber 14, as is illustrated at 15 in Figs. 3 and 4. The body 12 of the table, as is 100 particularly shown in Fig. 4, is provided with a series of radial slots 16, extending from its outer edge some distance into the beveled portion 15 of the body, and at the under face of said disk body 12 of the table, at the inner 105 end portions of the slots, ears 17 are formed, (shown by dotted lines in said Fig. 4,) which ears are pierced for the passage of bolts 18. Preferably the body member 12 of the table-section is provided with eight slots 16, as 110 illustrated, but this number may be increased or decreased, as desired.

In assembling the parts of the base A the hub member 13 of the table-section a' is slipped over the tubular standard 11, secured to the bottom section a , and a spring 19—usually a coiled spring—is loosely placed in the hub-chamber 14, as is shown in Fig. 3. A spindle 20 is passed through the spring 19 and the tubular standard 11 into the bottom chamber 10^a, where the spindle is exteriorly threaded to receive the two nuts 21 and 22. The spindle 20 extends some distance beyond the upper face of the table-section a' , terminating at its upper end in a head having a horizontal slot therein, and a set-screw 23 is made to enter the said slot.

Below the head of the spindle 20 and at the upper portion of the spring 19 two horizontal flanges 24 and 25 are integral with or are attached to the spindle, a space being made to intervene between the said flanges, as is clearly shown in Fig. 3. The flanges 24 and 25 are preferably made of such size that they may pass down within the spring 19 should occasion require. The upper portion of the spindle 20 in its normal position is so held by the spring 19; but the spindle is adapted to be drawn downward to release the framing members from the hat-frame at any time, as will be hereinafter particularly described. When the downward movement of the spindle 20 is made, the spring 19 is compressed and the downward movement of the spindle and its release or upward movement to normal position is effected as follows: A circumferential slot 26 is provided in the side of the body 10 of the bottom section a adjacent to the flange 11^a, and the said slot has a low section 26^a, which is quite close to the flange 11^a, a high section 26^b and an inclined intermediate section connecting the high and the low sections, as is best shown in Fig. 6. On the upper wall of the chamber 10^a in the bottom of the body member 10 a cam projection 27 is formed at the said slot 26, the under or working face of which cam projection 27 conforms to the shape of the upper wall of the said slot, being even therewith, as is shown in Figs. 5 and 6. The said cam projection 27 consists of a high member 27^a at the lower section of the slot 26, a shallower member 27^b at the high section of the slot, and an intermediate inclined connecting member. Immediately opposite the said cam projection 27 a second and corresponding cam projection 28 is formed upon the upper wall of the chamber 10^a, as is best shown in Fig. 5, and the positions of the members are just opposite to the positions of the members of the cam projection 27, as the shallower member 28^b of the cam projection 28 is opposite the higher or deeper member 27^a of the cam projection 27, the shallower member 27^b of the cam projection 27 being opposite the deeper or higher member 28^a of the cam projection 28, and

their connecting inclined sections therefore incline in opposite directions.

A lever 29 is passed into the chamber 10^a through the slot 26, being loosely connected with the lower end of the spindle 20 by the nuts 21 and 22, as is shown in Fig. 3, and, as is illustrated in Figs. 3 and 5, the said lever terminates in a foot 30, adapted to engage with the working face of the cam projection 28, while the body portion of the lever is in engagement with the working face of the cam projection 27. Thus when the lever 29 is carried to an engagement with the shallower sections of both cam projections 27 and 28 it will be at the higher end of the slot 26 and the spindle 20 can be carried to this higher position by the spring 19. When the lever 29 engages with the intermediate inclined members of the said cam projections, the spindle 20 will naturally be drawn down to a certain extent; but when the lever 29 engages with the deeper or higher members of the cam projections 27 and 28 the spindle 20 will be drawn down to the limit of its movement in that direction.

In order that the shifting lever 29 may be held in its adjusted position, rack-teeth 31 are formed upon the flange 11^a of the bottom member a in front of the slot 26, and a thumb-latch 32 is pivoted upon the lever 29 to engage with the said rack, as is shown in Fig. 3. When the hub member 13 of the base is in position on the tubular standard 11, the hub is prevented from being withdrawn and is yet free to turn on the tubular standard 13 by introducing a screw 33 into the hub and into an annular groove 33^a, exteriorly formed in the said tubular standard.

Although the flanges 24 and 25 are shown of slightly less diameter than the diameter of the spring 19, the said flanges may be of the same or of greater diameter, if desired.

The body or bed member 12 of the table-section a' carries shoes B, (shown particularly in Fig. 8,) and each shoe is adapted to carry a supporting-arm C, detachable therefrom and capable of radial and lateral adjustment upon the shoe. The shoes B correspond in number to the number of slots 16 in the bed or body plate 12 of the table-section a' and are of segmental shape, so that when all of the shoes are in position upon the said body or bed plate 12 they practically cover said body or bed plate, as is shown in Figs. 1 and 2. Each shoe B is independent of the others, yet all are given simultaneous rocking motion on the bed or body plate 12 when the spindle 20 is moved up and down. Each shoe at a point about centrally between its inner and outer end is provided with a downwardly-extending lug 34, and these lugs are passed down through the slots 16 of the said body or bed plate 12 to a position between opposing ears 17, and the shoes are hinged to or are pivot-

ally connected with the bed or body plate 12 by passing the bolts 18 heretofore referred to through the said ears and lugs, as is shown in Figs. 3 and 4.

5 It will be observed, especially by reference to Fig. 3, that the shoes have rocking movement on the body or bed plate 12 of the table-section a' by reason of the beveled or inclined surface 15 on the top of the plate beneath the inner portions of the shoes, enabling their inner ends to be depressed and their outer ends elevated when desired; but normally the shoes rest in a horizontal position.

The rocking movement mentioned is imparted to the shoes by the vertical movement of the spindle 20 and is brought about by forming a toe 34^a at the inner or contracted end of each shoe and introducing the toes into the space between the flanges 24 and 25 on the spindle 20, and the toe of one shoe is provided with a slot 35 therein, as is shown in Fig. 8, for a purpose to be hereinafter explained.

Each shoe B is provided with a yoke 36, 25 transversely located upon its upper face, open at the front and at the rear, and each yoke is provided with a segmental slot 37 in its upper portion, and in the same portion of each yoke a series of segmentally-arranged 30 apertures 38 are produced. The supporting-arms C, one of which is used in connection with each shoe B, are preferably inwardly curved at their inner ends and are straight or vertical at their outer ends when in position 35 for use, and each supporting-arm terminates at its lower end in a horizontal foot 39 or a foot extending inward at an angle to the body of the arm. The feet of the supporting-arms C are adapted to enter the yokes 36 40 of the shoes B and are of such shape that they may be turned in the said yokes, as on a pivot, or adjusted in direction of the sides of the machine as may be required without changing their relation to the center of the 45 machine.

The upper and lower faces of the feet 39 are flat, and the preferred general contour is substantially triangular, as is shown best in Fig. 2. Each foot is provided with a clamping-screw 40, which in practice is passed through the segmental slot 37 of a yoke 36 and into the foot, the screw being preferably provided with a square head. This arrangement enables each individual supporting-arm 50 to have independent pivotal and lateral adjustment and provides means for securing the arm in its adjusted position; but in order that each arm shall be firmly secured after adjustment a set-screw 41 is provided for 55 each series of apertures 38, which set-screw after the adjustment of a supporting-arm is screwed into one of the apertures 38 to a firm engagement with the inner end portion 60 of the foot of the arm, as no matter how a 65 supporting-arm C is adjusted in a shoe B

the inner end of the foot 39 of the arm will be beneath one or the other of the apertures of a series 38 in the yoke of the shoes, as is illustrated in Fig. 2.

The supporting-arms constitute a basket, 70 and, as stated, any one is independently adjustable and any one or more can be removed when not needed. Each supporting-arm is provided with an inwardly-extending carrier member D at its upper end, either integral 75 therewith or attached thereto. The carrier members D may be either in the form of slotted bars, as is shown in Figs. 1, 3, or 9, or may be solid, as illustrated at D' in Figs. 11 and 12.

In the drawings the carrier members D are shown screwed to the supporting-arms C, and in Figs. 1, 3, and 9 each member D is provided with a slot 42, extending longitudinally from top to bottom, and a second 85 slot 43, which extends longitudinally through from side to side, so that the said members D for the supporting-arms C are of skeleton construction.

Each carrier member D is provided with 90 any desired number of removable and adjustable clamps E. Each of these clamps consists of a block 44, mounted to slide in a side slot 43 of a carrier member, being provided with a threaded post 45 at one side 95 and an elongated aperture 46, extending through from top to bottom, the end walls of which apertures are preferably convexed, as is shown at the right in Fig. 9.

When a block 44 is placed in position in a 100 carrier member D, one side of the block is flush with one side of the carrier and the threaded post 45 extends beyond the other side of the carrier, while the aperture 46 in the block is longitudinally located with respect to the carrier. Finally, a thumb-nut 105 47 is placed on the threaded post 45.

The clamps E are prevented from leaving the carrier members D by passing the body portions 48 of framing members F through 110 the vertical slots 42 of the carriers and through the elongated slots 46 of the clamping-blocks 44, as is shown in Figs. 1, 3, 9, and 10. After a clamp has been adjusted in the carrier and a framing member F has been 115 adjusted in the clamp the parts are held in adjusted position by tightening up the thumb-nut 47, as is shown in Fig. 10, which nut by exerting pressure on one side of the carrier D causes the framing member passed 120 through the body-block of the clamp to be firmly wedged between the opposing longitudinal walls of the vertical slots 42 of the carrier at the point where that especial clamp is located, but will not interfere with the separate adjustment of other clamps on the 125 same carrier member.

The body portions 48 of the framing members F may be straight throughout or their upper portions 49 may be curved or given 130

any desired angle or inclination with reference to the main body portion as may be required in the formation of a hat-frame, as is shown in Fig. 3; but each framing member 5 terminates in a hook-head 50.

5 In the construction of a framing member F a round wire of suitable gage is usually employed, reduced at its upper end, so that the hook-heads 50 of the framing members 10 are materially of less diameter than their remaining portions, and the upper portion of the body is made to gradually taper where the reduction is made. The hook-heads 50 are substantially of S formation, the intermediate and lower members being brought 15 close together; but the intermediate and upper members are sufficiently wide apart to freely receive the wire employed in making a hat-frame. Under this construction of the 20 heads 50 it will be observed that no sharp points are presented to cut the framing-wire, and that the wire is really guided to the upper or receiving sections of the hook-heads.

25 In the further construction of the machine I employ a centering device G for the crown 30 of the hat-frame, which device is removable from the machine and is constructed for lateral and vertical adjustment, so that it may be adapted to any form of crown or any location 35 of crown with respect to the brim of the hat. This centering device consists of a base g and a body-section g'. The base g comprises two parallel horizontally-spaced members 51 and 52, located one above the other, the members 40 being connected at one end, and the lower member 52 is introduced into the slot heretofore mentioned, located in the head of the spindle 20, and is adjustably and removably held therein by the set-screw 23, carried by 45 the spindle 20, as is shown in Fig. 3. The body-section g' of the device comprises a lower tubular member 53, preferably enlarged at its lower end and provided at said end with a slot to receive the upper member 50 50 of the base-section g, being laterally adjustable upon said member, and the said tubular member 53 is held in adjusted position by a set-screw 54, carried thereby and which engages the aforesaid upper member 51 of the base-section.

55 A rod member 55 is telescopically placed in the tubular member 53, so as to obtain the vertical adjustment of the said centering device, and the rod member 55 is held in adjusted position by means of a set-screw 56, which set-screw is located at the upper portion 60 of the tubular member 53 and engages with the rod member 55, as is also shown in Fig. 3.

60 At the upper end of the rod member 55 a head 57 is located, and in the upper face of this head, which is preferably flat and of disk-like formation, a series of intersecting slots 58 is produced, the slots being usually 65 eight in number. These slots receive and

hold the central portion of the cross-wires which constitute the top of the crown of a hat and effectually hold the said wires in position, perfectly centered, while the other portion of the hat-frame is being constructed. 70

I desire it to be understood that any preferred means may be employed for capping the head 57 to prevent the wires from rising therefrom after they have been placed in position. 75

It will be observed that each particular clamp may be adjusted independently of its support and that each of the framing members employed in the actual formation of a hat-frame can be independently adjusted; 80 also, that any desired number of framing members may be permitted to remain in their clamps and the clamps loosened to permit such framing members as are not needed to be dropped down out of the way and yet 85 be at hand for immediate service.

A frame of any desired shape is first constructed by hand. The lever 29 of the machine is placed in its normal position, (shown in Fig. 3,) whereupon the spring 19 causes all 90 of the supporting-arms to take their normal positions, also shown in Fig. 3, and the centering device is adjusted to take the eight top wires H where they cross and is then secured in its adjusted position. Next the supporting-arms C are shifted or swung upon their pivots or are given both adjustments to bring their carrier members in proper relation to the center of the crown or the direction in which the eight main crown-wires H 95 may be led with reference to the circular wires H' of the crown and brim. After the adjustment of the supporting-arms C they are secured in position in the manner stated. 100 The various framing members F are now adjusted in their clamps, and the clamps are adjusted in their carrier members D to outline the circular wires H' of the frame at points where the main crown-wires H are to be secured thereto. After the proper outline 105 has been obtained all the clamps are firmly tightened up and the model is removed by carrying the lever 29 in a direction to draw the spindle 20 downward, and consequently all the carrier members and upper 110 portions of the supporting-arms C inward. The lever 29 is then returned to its normal position. The operator now proceeds to lay the main cross-wires H for the new frame in the slots 58 of the head of the centering device G and passes other wires around the various horizontal rows of hook-heads 50, thus producing the necessary circular wires H', each of which wires is suitably secured 115 at its ends. Finally, the main crown-wires H are carried in their proper alinement across the circular wires H', connecting them, and are secured to them in any approved manner. 120

In directing and manipulating the main 130

crown-wires H the operator does not change his position relative to the machine, but simply turns the body of the machine upon its bottom base member a until the desired point in the frame to be operated upon can be conveniently reached. In so turning the machine it is absolutely necessary that the position of the centering device G shall not change from its adjusted position relative to the supporting-arms C, and consequently all parts of the body of the machine must move together. Therefore the spindle 20 is compelled to turn with the table-section a' and the shoes B, and this is done by passing a pin 59 down through the upper flange 24 of the spindle 20 into the slot 35, heretofore referred to as produced in the inner end of one of the shoes and as is shown in Fig. 3. After the frame is completed the lever 29 is moved in a direction to draw the spindle 20 downward and the carrier members D inward, which releases the frame just completed from the hook-heads 50 of the framing members, and the hat-frame will spring from the machine of its own accord.

In order to render it absolutely certain that none of the carrying-arms C shall move inward through any possible downward movement of the spindle 20 after the carrying-arms have been set to their normal position when the lever 29 is in position to hold the said arms C in their normal position, the foot 30 of the said lever is held between the cam projection with which it engages and a lug 60, secured to an inner side wall of the bottom chamber 10^a.

It will be observed that by reason of the numerous adjustments for the supporting-arms C shown and described their carrier members at their inner ends may be set relatively to a given center and their outer ends adapted as required to any point in a circular circuit, enabling the framing members to be set to bring about the production of any shape, whether regular or exceedingly odd and irregular, both with respect to the crown and the brim portion of the hat.

In Figs. 11 and 12 I have illustrated the preferred form of carrier D' for the supporting member C in which the said member is a solid bar, rectangular in cross-section, and the clamps E' for this bar are made in two members e and e'. Each clamp member e and e' adjacent to one end is provided with a rectangular recess 61 in its inner face, so that when the two members are brought together the two recesses being one opposite the other produce a rectangular opening in which the carrier-bar D' is more or less snugly accommodated, and at the opposite end of the two members e and e' transverse spacing-ribs 61^a are formed to maintain the members in proper alinement when in position on the carrier-bar, as they do not meet over the bar 65 at their opposite ends, and in the further con-

struction of the members e and e' alining apertures 62 are made in them between the recesses 61 and the spacing-ribs 61^a. When the members e and e' are in position on a carrier bar or member D', a screw E² is passed through them, having a head 63 at one end, the opposite end being reduced and threaded, and the said screw E² is provided with an aperture 64, partly in its head and partly in its neck, which aperture 64 is sufficiently large to permit the passage of the body of a framing member F. After the members of the clamp are in position on the carrier-bar D' and the screw E² is in position in the said members a thumb or other form of nut 65 is loosely screwed upon the threaded portion of the screw E², and then the body portion of a framing member is passed through the aperture 64, whereupon by tightening up the thumb-nut 65 the clamp is firmly held on the carrier-bar D' and the framing member F is also firmly held in the clamp. The head of the screw E² is made flat and smooth with rounded edges, so as not to interfere with the passage of the wire to the hook-heads 50 of the framing members F. This form of clamp can be made to extend up or down from the carrier-bar D' and be equally effective in either position. It is evident that the clamp is readily adjustable on the carrier-bar and that the framing member can be quickly and conveniently adjusted in the clamp.

Having thus described my invention, I claim as new and desire to secure by Letters Patent—

1. In wire-framing machines, supporting-arms for framing members, a support for said arms, and an adjustable connection between the arms and support, whereby the said arms can be adjusted in a circumferential direction toward and from each other.

2. In wire-framing machines, supporting-arms for framing members, a support for said arms, and means for pivotally and loosely mounting the arms on the support, whereby the said arms can be pivotally and bodily adjusted in a circumferential direction toward and from each other.

3. In wire-framing machines, supporting-arms for framing members, a swinging support for each of said arms, and means for connecting the arms with the supports, whereby the arms can be adjusted in a circumferential direction toward and from each other.

4. In wire-framing machines, supporting-arms for framing members, a support upon which said arms are removably and pivotally mounted, and means whereby the arms can be adjusted in a circumferential direction toward and from each other.

5. In wire-framing machines, supporting-arms for framing members, provided with lower foot-terminals, a table-support, shoes mounted upon the table-support, yokes carried by the said shoes, adapted to loosely re-

ceive the foot members of the supporting-arms, sliding pivots for the foot members of the said arms, and locking devices for the said foot members.

5. In wire-framing machines, a supporting-table provided with a shoe comprising a body-section and a yoke at the upper portion thereof provided with a slot and a series of apertures adjacent to the slot, a supporting-arm for framing members, having a foot at the lower end adapted to enter the shoe, which foot is of less diameter than the width of the shoe, a pivot-bolt passed through the slot in a shoe into the foot member, being 15 slideable in said slot, and an adjustable locking device adapted to enter any of the said apertures.

7. In wire-framing machines, a rotatable table-support, receivers mounted for rocking 20 movement upon the table-support, supporting-arms for framing members having their lower ends fitting in the receivers, said ends being capable of lateral sliding movement in the receivers, combined pivotal and locking 25 devices for the said foot-terminals, also capable of lateral movement in the receivers, and means for raising and lowering an end portion of the said receivers.

8. In wire-framing machines, a main support, receivers mounted upon the main support, supporting-arms for framing members located on the said main support and having 30 foot-terminals adapted to enter the receivers, being capable of lateral movement therein, combined locking and pivotal elements for the said foot members, having lateral movement in said receivers, and auxiliary shiftable locking elements for the said foot members also carried by the receivers.

40. 9. In wire-framing machines, a centering device having lateral and vertical adjustment.

10. In wire-framing machines, a support and a centering device comprising a base-section adjustably carried by the support, 45 and a body-section laterally adjustable upon the base-section and consisting of telescopic members and a locking device for the members.

11. In wire-framing machines, a support 50 and a centering device comprising a base-section consisting of two parallel connected members, one above the other, which base-section is removably and adjustably connected with the support, and a body-section 55 consisting of telescopic members, the lower one of which is adjustably mounted on the base-section, a locking device for the two members, and a head for the upper member provided with connected radial slots to receive the main crown-wires of a hat-frame.

60. 12. In a wire-framing machine, a main support, a basket of supporting-arms carried by the main support, each arm being provided with an inwardly-extending carrier member for framing members, each arm having

independent lateral and pivotal adjustment on the main support, whereby the inner ends of the carrier members may be set relatively to a given center and their outer ends adapted to any point in a given circuit. 70

13. In wire-framing machines, a carrier-arm for framing members, clamps for the said carrier-arm, which clamps are constructed in two independent sections recessed upon their inner faces to receive the said bar and 75 provided with apertures adjacent to the said recesses, a screw having a head at one end and a nut at the opposite end, the said head being provided with an aperture to receive the body portion of a framing member, for 80 the purpose herein set forth.

14. In a wire-framing machine, a rotatable table, supporting-arms mounted to rock upon the said table, carrier members secured to the supporting-arms, which carrier members 85 are adapted to receive and hold wire-framing members, a spring-controlled spindle passed through the said rotatable support, having vertical movement therein and controlling the rocking supports for the said supporting-arms, a base upon which the rotatable support is mounted, cam-surfaces provided for the said base, and a lever loosely mounted on the said spindle and adapted for engagement 90 with the said cam projections to permit the 95 rise and fall of the said spindle.

15. In wire-framing machines, a table, a sliding spindle, shoes pivoted on the table and operatively connected with the spindle, supporting-arms for framing members, said 100 arms being adjustably secured to the shoes to permit them to be moved toward and from each other, and means for sliding the spindle.

16. In wire-framing machines, a slotted 105 rotary table, a spring-pressed and sliding spindle, shoes pivoted in the slots of the table and operatively connected with the spindle, supporting-arms for framing members, pivoted to the shoes, means for locking 110 the arms in position, and means for sliding the spindle.

17. In wire-framing machines, a rotatory table, a sliding spindle projecting above the table, supporting-arms for frame members, 115 pivotally connected with the table and engaging the spindle, means for sliding the spindle, and a centering device, comprising a base adjustably secured to the upper end of the spindle and telescopic members, the 120 lower one of which is adjustably secured to the base.

18. In a device of the class described, the combination of a central upright member having a head, a series of radially-arranged 125 clamping-arms each independently hinged to the head on the central upright member and means to support the same in a horizontal or angular position.

19. In a device of the class described, the 130

combination of wire-holders with a series of radially-arranged clamping-arms each independently hinged to a head on the upper end of a central upright member, the said clamping-arms arranged to hold the wire-holders in a perpendicular position.

20. In a hat-frame-forming device a series of radially-horizontal arms each hinged to the head of an upright support, means for holding each arm in relatively the same horizontal or angular position, a clamping means to individually secure to each horizontal arm one wire-holder for the round-and-round wire for the head size for the hat-frame.

15 21. In a device of the character described, the combination of an upright member supporting radially-arranged clamping-arms capable of relative movement, a series of wire-holders clamped to each of said radially-arranged arms and a center directing-pin which is capable of vertical adjustment.

22. In a device of the class described, the combination of wire-holders with a series of radially-arranged and hinged clamping-arms adapted to support a required number of wire-holders, means permitting radial adjustment of each wire-holder, means to hold the same in position, and a collapsible means to free the completed wire hat-frame.

25 30 23. A wire-hat-frame-forming device pro-

vided with radially-arranged arms composed of two detachably-connected parts, the outer parts of said arms being provided with vertically-arranged and vertically-adjustable arms, which are pivoted thereto, and adapted to swing in vertical and radial planes.

24. A wire-hat-frame-forming device provided with radially-arranged arms composed of two detachably-connected parts, the outer parts of said arms being provided with vertically-arranged and vertically-adjustable arms, which are pivoted thereto and adapted to swing in radial and vertical planes, and which are also radially adjustable.

25. An adjustable form for making wire hat-frames comprising a support, a series of pivoted divergent arms carried by said support adapted to swing laterally on their pivots, means for securing said arms in their adjusted positions, a series of wire-holding devices carried by said arms, and means for simultaneously moving the wire-holding devices to release the hat-frame.

In testimony whereof I have signed my name to this specification in the presence of two subscribing witnesses.

ABRAHAM VELLEMAN.
